TOY

Filed Aug. 31, 1923

Bernard P Johnson

UNITED STATES PATENT OFFICE.

BERNARD P. JOHNSON, OF CINCINNATI, OHIO.

TOY.

Application filed August 31, 1923. Serial No. 660,349.

To all whom it may concern:

Be it known that I, BERNARD P. JOHNSON, a citizen of the United States, residing at Cincinnati, in the county of Hamilton and 5 State of Ohio, have invented new and useful Improvements in a Toy, of which the following is a specification.

This invention relates to a dancing doll which is designed to be operated by some 10 mechanical contrivance such as the table of a phonograph.

An object of my invention is to produce a doll in which the movements of the human figure are accurately reproduced in a novel 15 manner by very simple mechanism and which may be produced cheaply.

This and other objects of my invention are attained in the construction described in the following specification and illustrated in 20 the accompanying drawing in which:

Fig. 1 is an elevational view of a doll embodying my invention.

Fig. 2 is a longitudinal sectional view taken on the line 2—2 of Fig. 1, but upon a 25 materially reduced scale.

Fig. 3 is a fragmental perspective view of a detail of my invention.

In the construction of my improved toy, I provide frame members 4 and 5 the latter 30 extending vertically to support the doll and the former extending horizontally for suitable mounting at some point beyond the phonograph turn table 6. Upon the upper end of support 5 I attach the torso 7 of 35 the body of the doll. This torso carries the head 8. At the upper end of the torso the shoulder and breast portion 9 is mounted for vertical reciprocation by means of a pin 10 in a slot 11 in the torso. The hip portion 40 12 is attached to the torso by means of a pin 13 which is adapted for reciprocation vertically in a slot 14 of the torso. In order to communicate motion to the breast portion from the hip portion I attach pivotally the 45 arm section 15 as shown, the other arm 16 being positioned in characteristic dancing posture. The lower portion of the hips is provided with pivots 17 and 18 to which the thigh sections 19 and 20 of the legs are attached, the feet 21 and 22 being supported by pins 23 and 24 to permit the hips to rock 50

sidewise as well as upwardly and downwardly.

Back of the figure I mount a wheel 25 which is designed for frictional engagement 55 with the surface of the turntable 6 and is pivoted at a point 26 on support 5. On the wheel a pulley 27 is mounted for driving a belt 28 which passes over an upper pulley 29 pivoted at a point 30 on the support 5. 60 A crank pin 31 attaches the hip portion 12 to the pulley so that when rotated a circular motion will be imparted to the lower portion of the hips. Upon pulley 29 a square cam 32 is attached. This cam operates, in 65 pendulum fashion, the depending end 33 of a support member 34 which carries pin 10 to which the breast is attached. A sidewise hooked projection 35 retains support 34 by resting at its outer end upon a plate 36 70 of support 5. Thus when cam 32 rotates, the end 33 gives support 34 a vertical reciprocatory movement. A feature of my invention is the adjustable pivot member 37 by means of which the drive wheel 25 is 75 held in position relatively to the center pin 38 of the turntable so that the wheel may be placed at the adjusted distances therefrom to give it the desired speed of rotation.

In the operation of my improved toy I 80 place the device in the position I have described above and then start the turntable. Rotation of wheel 25 will create a side wise hip movement which also has imparted thereto simultaneously a slight upward and downward movement. This is accompanied 85 by a slight rocking of the breast portion which is also given a more or less rapid vertical vibratory movement. The resultant combination of movements is decidedly life-like and amusing.

Having thus described my invention what I claim is:—

1. A dancing doll comprising a figure having vertically movable hip and breast portions, mechanism adapted to impart to both portions a rocking movement and to the hip portion a simultaneous vertical movement, and additional mechanism adapted to impart to the breast portion an independent vertical movement of greater frequency than that of the hips.

2. A dancing doll comprising a figure having relatively movable breast and hip portions, a crank connected to the hip portion and adapted to give said portion a substantially rotary movement, and a cam co-operating with the crank adapted to impart a vertical movement, said portions being connected to impart a rocking movement to

the breast simultaneously with the vertical movement thereof.

In witness whereof, I affix my signature in the presence of two witnesses:

BERNARD P. JOHNSON.

Witnesses:

JOSEPH A. SULLIVAN,
WILLIAM J. SCHULTZ.
